UNITED STATES PATENT OFFICE.

CLINTON A. TOWER, OF CLEVELAND, OHIO, ASSIGNOR TO THE NATIONAL
MALLEABLE CASTINGS COMPANY.

CAR-COUPING.

SPECIFICATION forming part of Letters Patent No. 734,146, dated July 21, 1903.

Original application filed May 29, 1902, Serial No. 109,477. Divided and this application filed May 2, 1903. Serial No. 155,251. (No model.)

To all whom it may concern:

Be it known that I, CLINTON A. TOWER, of Cleveland, Cuyahoga county, Ohio, have invented a new and useful Car-Coupler, of which the following is a full, clear, and exact description, reference being had to the accompanying drawings, forming part of this specification, in which—

Figure 1 is a plan view of two coupler-heads A B, having my improved devices shown in locked position, one of the coupler-heads being partly in horizontal section for purposes of illustration. Fig. 2 is a vertical longitudinal section on the line II II of Fig. 1, the coupler A being shown with its locking and opening piece in lock-set position and the other in locked position. Fig. 3 is a horizontal section of one of my improved couplers having its knuckle thrown forward. Fig. 4 is a vertical cross-section on the line IV IV of Fig. 3, and Fig. 5 is a vertical section showing the locking and opening piece in front view.

My present application is a division of a patent granted to me on May 12, 1903, No. 728,049.

In the drawings, 2 represents the coupler-head, and 3 is the knuckle, whose tail 3' extends rearwardly from the pivot-pin 4, the front side of the tail or the end portion thereof being preferably approximately parallel with the central line of the draw-bar when the knuckle is locked.

The locking and opening piece 5, in so far as its locking function is concerned, is in the nature of a pin, which extends on the front side of the tail of the knuckle and in locking has a bearing against the coupler-head extended both above and below the knuckle. Its lower end is shaped to constitute a tongue or toe b, which is inclined forwardly and adapted to fit in a correspondingly-inclined hole 6 in the floor of the coupler. Its upper end or head has a forward projection c, or it is otherwise suitably shaped for pivotal attachment to a lifting-link 7, and at the rear of the head is a bearing d, which is adapted to engage a fulcrum 8 at the top of the recess 9 of the coupler-head, in which the piece 5 is set.

This recess is preferably nearly of the same width as the piece 5, so that it may guide and steady the latter. At the rear of the locking and opening piece is a heel e, and it has a lateral extension f, adapted to make initial engagement with the knuckle when the latter is being opened.

When the parts are in the position shown at the coupler B in Fig. 2, the knuckle is closed and locked, and the locking and opening piece 5 fits in front of the knuckle-tail, with its toe or guiding portion b in the hole 6, the projection c fitting in a recess n in the coupler-head and the heel e resting on the floor of the coupler and keeping the piece 5 tipped forwardly, so that the projection c thereof will be maintained in the recess. The piece 5 is thus locked and cannot be made to jump or creep upwardly by the jarring of the car. The parts c and n are kept in engagement by the free forward tipping of the lock on the heel e, which rests on the floor of the coupler, the heel being back of the center of gravity of the piece 5; but these parts are disengaged readily as soon as the piece is lifted. This is important and constitutes the point of invention which I claim herein. If it is desired to unlock the knuckle and to swing it open, the operator lifts the link 7. This causes the piece 5 to rise, and during its first motion the guiding portion or toe b at its lower end moves it rearwardly until it has passed back of the path of the tail of the knuckle and has left the latter free to swing open and its head has engaged the fulcrum 8 at the top of the coupler-head. The piece 5 is then in knuckle-throwing position, and continued lifting of the link 7 will cause it to tip forwardly on the fulcrum 8, whereupon the projection f will engage the knuckle initially, and the toe b will then move the knuckle open, as shown in Fig. 4. The operator having thus opened the knuckle can allow the piece 5 to drop into the position shown by dotted lines in Fig. 4. When the knuckle is next swung into closed position, its tail will engage the piece 5 and will push it back until its toe b comes into register with and drops into the hole 6, whereupon the parts will be re-

stored to the locked position above described and shown at the coupler B of Figs. 1 and 2.

The skilled mechanic will be able to modify the parts of my coupler in various ways, so 5 as to accomplish the results above stated substantially as I accomplish them by the device shown in the drawings. The locking and opening piece is easy in all of its motions and throws the kuckle forwardly to as great extent as 10 desired, and the locking of the lock is performed in a simple and effective manner.

The coupler can be made of light weight without sacrificing the strength required in service.

15 I claim—

1. A coupler having a knuckle, a locking-piece, and a retaining-recess for said piece when locked, said piece being supported back

of its center of gravity on a forwardly-inclined tongue b, and having at the rear thereof a heel which bears on the floor of the coupler, whereon it is tipped by gravity into the recess; substantially as described. 20

2. A coupler having a knuckle, a locking and opening piece, and a retaining-recess for 25 said piece when locked, said piece being supported back of its center of gravity on a bearing on the floor of the coupler, whereon it is tipped by gravity into the recess; substantially as described. 30

In testimony whereof I have hereunto set my hand.

CLINTON A. TOWER.
